UNITED STATES PATENT OFFICE.

SAMUEL M. CURWEN, OF VILLANOVA, PENNSYLVANIA, ASSIGNOR TO
JOHN A. BRILL, OF PHILADELPHIA, PENNSYLVANIA.

CAR.

SPECIFICATION forming part of Letters Patent No. 761,627, dated May 31, 1904.

Original application filed August 21, 1903, Serial No. 170,258. Divided and this application filed November 24, 1903. Serial No. 182,464. (No model.)

To all whom it may concern:

Be it known that I, SAMUEL M. CURWEN, a citizen of the United States, and a resident of Villanova, county of Montgomery, State of Pennsylvania, have invented certain new and useful Improvements in Cars, of which the following is a specification.

The object of my invention is to construct a car, more especially the so-called "semi-convertible" type, in which sashes drop into pockets in the side of the car, using commercial forms of angle-irons to give increased strength, to reduce the cost, and secure compactness.

15 This is a division of application Serial No. 170,258, filed August 21, 1903.

I have devised a car wherein the lower sashes are adapted to be lowered into pockets, the lower ends being below the floor-level.

20 The side posts or stanchions are bolted on the outside of the longitudinal angle-iron sill and to a horizontal truss-plank, which latter bears on the iron sill. Either the sill or truss-plank may support the flooring, although in 25 this divisional application I show and describe the flooring as supported by the sill.

For a more particular description of my invention reference is to be had to the accompanying drawings, in which—

30 Figure 1 is a perspective sectional view of a portion of the frame embodying my improvements. Fig. 2 is a sectional view taken on the line 2 2 of Fig. 1 looking in the direction of the arrows.

35 Throughout both views similar reference characters designate similar parts.

As my invention relates more particularly to the sill, stanchions, truss-plank, and flooring, all other parts which are not necessary 40 to bring out this structure are omitted and only a portion of the side of the frame is shown, it being understood that the frame

may be of the conventional type except as herein noted.

The side sill 1 comprises an inverted bulb-iron with a flange 2 extending inwardly in one direction only, at its top, and a bulb-flange 3 at its lower extremity, which also extends inwardly. To strengthen and reinforce this sill, a truss-board 4 is bolted by bolts 5 45 on the flange 2, so that the lower edge of this plate rests against a part of the horizontal surface, as shown in Fig. 1. The stanchions 6 are bolted by bolts 7 to the vertical web of the side sill 1 and to the truss-board 4. These 55 stanchions terminate a little above the lower edge of the sill 1 and are provided with sash-grooves 8. The lower ends of the stanchions are united by boards 9, 10, and 11, the two latter being mortised in the outer edges, and 60 the sheathing 12 on the outer surface of the car is secured to the stanchions 6 in the customary manner. The base-board 13 rests on the truss-board 4 and is recessed at 14, so as not to interfere with the bolts 5. From this 65 it is obvious that the side sill 1 is reinforced and stiffened by the truss-board 4 and stanchions 6, so that a very light and rigid frame may be produced in this way.

The flange 2 extends far enough beyond the 70 truss-board 4 to readily support the flooring 15.

Having described my invention, I claim—

1. A car or similar vehicle, having a side sill composed of a bulb-iron with a vertical 75 web and a horizontal web extending inwardly from its upper edge, a longitudinal truss-plank secured to the said horizontal web, a car-flooring resting on said flange, stanchions, and means for securing the stanchions to said sill. 80

2. In a car or similar vehicle, a side sill, composed of a bulb-iron having an inwardly-extending flange at the top, a longitudinal truss-plank fixed to the upper surface of said

sill, and car-flooring resting on said flange, stanchions, and bolts uniting said truss-plank, sill and stanchions.

3. In a car or similar vehicle, an angle-metal side sill with stanchions fixed to its exterior surface and a plank secured to the lower side of said stanchions.

4. In a car or similar vehicle, an angle-metal side sill with a horizontally-disposed web at its upper surface, grooved stanchions secured

to the exterior of said sill and a plank fixed to the lower ends of said stanchions and adapted to form the bottoms of sash-pockets.

Signed in the city and county of Philadelphia, State of Pennsylvania, this 19th day of 15 November, 1903.

SAML. M. CURWEN.
